(57) **CLAIM**

The ornamental design for a housing for cable transition assembly, as shown and described.

DESCRIPTION

FIG. 1 is a front perspective view of our new design for a housing for cable transition assembly.

FIG. 2 is a rear perspective view thereof, with the housing rotated ninety degrees about a longitudinal axis thereof from the position in FIG. 1.

FIG. 3 is a left side elevation view of the design in FIG. 1.

FIG. 4 is a right side elevation view thereof.

FIG. 5 is a top plan view thereof.

FIG. 6 is a bottom plan view thereof.

FIG. 7 is a front elevation view thereof; and,

FIG. 8 is a rear elevation view thereof.

The broken lines shown in the drawings illustrate portions of the housing for cable transition assembly and other environmental structure, such as, for example, a furcation tube jacket array and cable jacket, which form no part of the claimed design.
